Primary Examiner — Rhea Shields(74) *Attorney, Agent, or Firm* — Stephen R. Bylciv, Esq.(57) **CLAIM**

The ornamental design for a pedicle screw torque driver, as shown and described.

DESCRIPTION

FIG. 1 is a top perspective view of a pedicle screw torque driver, showing my new design;

FIG. 2 is a front view thereof;

FIG. 3 is a left side view thereof;

FIG. 4 is a top plan view thereof;

FIG. 5 is a bottom plan view thereof;

FIG. 6 is a rear view thereof; and,

FIG. 7 is a right side view thereof.

In the drawings, the broken lines are for the purpose of illustrating environment only and form no part of the claimed design.

1 Claim, 4 Drawing Sheets(56)
